UNITED STATES PATENT OFFICE.

JACOB KNOPP, OF BEAVER, OHIO.

FORCING ATTACHMENT FOR LIFT-PUMPS.

SPECIFICATION forming part of Letters Patent No. 364,655, dated June 14, 1887.

Application filed November 11, 1886. Serial No. 218,608. (No model.)

To all whom it may concern:

Be it known that I, JACOB KNOPP, a citizen of the United States, residing at Beaver township, in the county of Mahoning and State of Ohio, have invented certain new and useful Improvements in Forcing Attachments for Lift-Pumps; and I do hereby declare the following to be a full, clear, and exact description of the invention, such as will enable others skilled in the art to which it appertains to make and use the same.

My invention relates to pumps, and has for its object the construction of an attachment to be applied to ordinary lift-pumps for the purpose of forcing water.

The invention will be hereinafter fully described, and particularly pointed out in the claims.

In the accompanying drawings, which form a part of this specification, Figure 1 is a perspective (partly in section) of an ordinary lift-pump with my attachment applied thereto; and Fig. 2 is a vertical section of the attachment on an enlarged scale.

Reference being had to the drawings and the letters marked thereon, A represents a lift-pump, provided with a handle, B, a spout, C, and the other usual appendages of such pumps. (Not shown.)

D represents my forcing attachment, which consists of a cylinder, E, open at the top and provided with screw-threads *a* at the bottom, by which it is attached to the screw-threaded projection *a'* of the section F, as shown. The cylinder is also provided with a piston, b, which has an aperture, c, through it controlled by a check-valve, d; and in the lower end of the cylinder is a bottom, e, which is seated in a rabbet in the section F. The bottom has an aperture, f, in it controlled by a check-valve, g, which is closed by a spring, h, secured to the upper side of the valve and to a rod or bar, i, which rests upon the upper side of the bottom e.

G represents an air-chamber supported by a tubular arm, H, which forms an integral part of the section F, but may, however, be made separate therefrom and attached to it by screw-threads in the usual manner.

In the section F is formed a chamber, k, which communicates with the cylinder E and the air-chamber and with a discharge-passage,

l, in a nipple, m, to which a section of hose, n, is attached for conducting the water being forced to any desirable place. The section 55 F is also provided with a bracket, o, for securing the attachment to the pump-stock.

The piston of the cylinder E is connected to the pump-handle B at *p*, and is operated thereby during each stroke of the handle; and 60 the pump A and the cylinder E are connected by a detachable conductor, I, which engages with the pump-spout C and with a projecting nipple or branch, q, formed on the exterior of the cylinder.

The conductor may be made of metal, rubber hose, or other flexible material. The nipple *q* may be connected directly to an aperture in the pump-stock, thus dispensing with the conductor I, if desired; and the nipple *m* may 70 be placed in different positions to suit different pumps.

By the application of my attachment to lift-pumps water may be forced to a considerable distance, and applied to raising water to elevated tanks in buildings for the extinguishment of fires about the premises, for washing vehicles, for sprinkling lawns, and other useful purposes.

Having thus fully described my invention, what I claim is—

1. A pump attachment consisting of a cylinder and an air-chamber connected to and supported by an intermediate section provided with a discharge-nipple, and a bracket 85 for attaching it to an ordinary pump, substantially as described.

2. A pump attachment consisting of a section provided with a bracket for securing it to a pump-stock, a lateral tubular extension 90 surmounted by an air-chamber, a vertical projection supporting a cylinder having a supply-inlet near the upper end thereof, a discharge-nipple opposite to the cylinder, and a valve between the cylinder and the chamber in said section, in combination with a valved piston, substantially as described.

3. The combination of an ordinary lift-pump and a separate detachable forcing attachment secured to the pump-stock and connected with a discharge-orifice thereof, and having its piston connected to the handle by which the lift-pump is operated, substantially 100 as described.

4. The combination of an ordinary lift-pump provided with a discharge-spout, a separate and detachable forcing attachment secured to the stock of the pump, and a conductor connecting the cylinder of the attachment with the spout of the pump, substantially as described.

5. The combination of a pump provided with a handle and a discharge-spout, a detachable forcing attachment secured to the pump-stock with its piston connected to the

pump-handle, and a detachable conductor between the pump-spout and the cylinder of the attachment, substantially as described. 15

In testimony whereof I affix my signature in the presence of two witnesses,

JACOB KNOPP.
